UNITED STATES PATENT OFFICE.

M. MAURICE DIMOND, OF NEW YORK, N. Y.

FLUID-GAGE.

1,231,339.

Specification of Letters Patent. Patented June 26, 1917.

Application filed December 30, 1916. Serial No. 139,746.

To all whom it may concern:

Be it known that I, M. MAURICE DIMOND, a citizen of the United States, and a resident of the city of New York, borough of 5 Manhattan, in the county and State of New York, have invented a new and Improved Fluid-Gage, of which the following is a full, clear, and exact description.

My invention relates to fluid gages particularly adaptable for use in connection with gasolene tanks employed on motor vehicles.

An object of the invention is to provide a simple, inexpensive and efficient indicator 15 which can be manufactured at comparatively low price.

With the above and other objects in view, the nature of which will more fully appear as the description proceeds, the invention 20 consists in the novel construction, combination and arrangement of parts as herein fully described, illustrated and claimed.

In the accompanying drawings, forming part of the application, similar characters 25 of reference indicate corresponding parts in all the views.

Figure 1 is a section through the container provided with a gage embodying my invention;

30 Fig. 2 is an enlarged sectional view through the plug showing the indicator in locked position; and

Fig. 3 is a plan view of the plug.

Referring to the drawings, 4 is a container for liquid. It has an interiorly threaded collar 5 into which fits a plug 6. The plug has a recess in the top divided by a diametrical ridge 7. The ridge is enlarged in the central portion, as shown at 8 and 40 bored to accommodate a stem 9. The bottom of the plug has preferably a collar 10 which forms a guide for the stem at the plug. The stem 9 at one end thereof has a valve head 11 to fit snugly a tapering seat 12 formed on the central enlargement of the ridge. The 45 valve seat 12 is preferably depressed from the surface of the ridge for the purpose which will appear hereinafter.

The other end of the stem is anchored to a cork float 13 by making a tight fit between 50 the bore in the float and the tubular member, and by coating the tubular member with shellac before forcing the same into the float, the shellac cementing the tubular member to the float. This provides a cheap and 55 sure way of securing the float to the tubular member. The tubular member has a plurality of perforations 14 which serve as indicating means for the gage. Normally the head 11 of the stem 9 is maintained on the 60 seat 12 against the buoyancy of the float by a yielding member 15 in the shape of a flat spring, one end of which is anchored by means of a rivet 16 to a projection 17 formed within the recess of the plug 6. 65

The movement of the spring is limited by shoulders 18 which are formed by depressing the central portion of the ridge, as has been previously mentioned. The depression in the ridge to each side of the bore 70 is sufficient for the spring to clear the valve head. The top of the head is preferably slightly curved to facilitate the engagement of the spring with the head when the float is forced into the liquid body to lock the 75 valve on its seat.

I claim:

A liquid gage comprising a plug having a recess in the top thereof, a diametrical ridge in the recess presenting an enlarged 30 portion having a central aperture, a tubular stem fitting into the aperture and presenting a tapering valve head at one end thereof, said central, enlarged portion of the ridge presenting a tapering valve seat at 35 the aperture for said head, said valve seat being depressed from the surface of the ridge, a tubular extension from the bottom of the plug serving as a guide for the stem, a flat spring anchored to the plug within 40 the recess for engaging the valve head of the stem to retain the same on the seat, and a float anchored to the stem.

M. MAURICE DIMOND.
